Primary Examiner — Richard Kearney*Assistant Examiner* — Benjamin M Weeks(74) *Attorney, Agent, or Firm* — Martin E. Hsia; Keri Ann K. S. Krzykowski(57) **CLAIM**

The ornamental design for a brace, as shown and described.

DESCRIPTION

FIG 1. is a front, top, left, perspective view of a brace showing my new design;

FIG. 2 is a top plan view thereof;

FIG. 3 is a bottom plan view thereof;

FIG. 4 is an elevational view thereof from the front;

FIG. 5 is an elevational view thereof from the rear; and,

FIG. 6 is an elevational view thereof from the left, the elevational view from the right being the mirror image. The broken lines shown in FIGS. 1-6 illustrate portions of the brace that form no part of the claimed design.
